Patented Oct. 29, 1968

212,554

SKI SUPPORTING BRACKET

Leon J. Pratt, Trailsend Drive,
Canton, Conn. 44730

Filed Dec. 14, 1967, Ser. No. 9,783

Term of patent 14 years

(Cl. D54—1)

FIG. 1

FIG. 2

FIG. 3

FIG. 4

FIG. 5

FIG. 1 is a perspective view of a ski supporting bracket embodying my new design;

FIG. 2 is a side elevation as seen from the right of FIG. 1;

FIG. 3 is a rear elevation thereof;

FIG. 4 is a top plan view thereof; and

FIG. 5 is a bottom plan view thereof.

I claim:

The ornamental design for a ski supporting bracket, as shown.
